UNITED STATES PATENT OFFICE.

ALOYSIUS McHUGH, OF DU BOIS, PENNSYLVANIA.

THILL-COUPING.

SPECIFICATION forming part of Letters Patent No. 355,275, dated December 28, 1886.

Application filed November 3, 1886. Serial No. 217,893. (No model.)

To all whom it may concern:

Be it known that I, ALOYSIUS McHUGH, a citizen of the United States, residing at Du Bois, in the county of Clearfield, State of Pennsylvania, have invented a new and useful Improvement in Automatic Gravity-Locks for Couplings, of which the following is so full, clear, and exact a description as will enable others skilled in the art to which my invention appertains to make and use the same, reference being had to the accompanying drawings, in which—

Figure 1 is a side elevation of my improved coupling. Fig. 2 is a perspective of the same, showing it taken apart. Fig. 3 is a modification of same showing the gravity-latch provided with an additional weight on its front portion. Fig. 4 is another modification showing the gravity-latch held in position by a secondary locking device to prevent accidental displacement when the vehicle or other article to which this may be attached is inverted. Fig. 5 is a view of another modification showing the hook portion of the gravity-latch provided with an additional lug or projection which holds in this instance a rubber roll or sleeve which encircles the tie-bolt which joins the two forked ends of the tang B.

The object of my invention is to construct a coupling which may be quickly and easily operated without the necessity of using a wrench or any device whatever aside from the coupling itself.

Another object of my invention is to provide a coupling which will automatically lock itself as soon as the parts are secured together.

Another object of my invention is to construct a device without screws or nuts which will be likely to work loose. The device is adapted to be used more as a thill-coupling of vehicles; but it is quite apparent that it may be used for coupling purposes elsewhere, and I do not wish to be understood as limiting myself to its use in a thill-coupling.

In the accompanying drawings, A designates the usual bracket-support, which is secured to the axle of a vehicle in the usual manner by bolts or rivets. The front portion of this bracket is provided with a lug which projects upward. It is perforated at a to re-

ceive the rivet b, which holds the gravity-latch C in place on the lug on the bracket. Somewhat back of the perforation a is a projection, a'. Directly beneath the perforation a is a slot or recess, c, which is adapted to receive and accommodate the tie-bolt d, which is secured to the bifurcated ends of the tang B. To the rear of this slot c is a projection, d', the front face of which slants diagonally at an angle to correspond with the diagonal slant of the rear portion of the projection a' on the bracket A. The gravity-latch C is pivotally secured at a to the front portion of the lug on the bracket A.

It will be observed that the gravity-latch is pivoted eccentrically, or out of alignment with the center of gravity, which causes it to automatically drop to the position shown in Figs. 1 and 2, where it remains until it is lifted out of place and turned part way round to release the coupling when it is desired to remove the cross-bolt which joins the two bifurcated ends of the tang B. This gravity-latch is provided with a recess, b', the upper face of which extends in a straight line from about one-half way across the gravity-latch a slight distance to the rear, and then curves up to the top portion of gravity-latch in such a manner that the gravity-latch may be turned completely around by lifting its forward end up, and none of the material of which the gravity-latch is constructed will strike the cross-bolt, which is secured to the bifurcated ends of the tang B. Below the recess in the gravity-latch is a hook, e, which extends down horizontally, and its rear portion, e', engages with the bottom of the slot or cross-bolt which unites the bifurcated ends of the tang B.

From the above it will be observed that when the coupling is locked in position there will be no liability of accidental displacement of the parts, and the couplings may be uncoupled in a very short space of time with little effort and slight expenditure of physical force, and without the use of other devices—such as wrenches, punches, &c.—to undo couplings.

The operation of the device is as follows: When it is desired to couple the two portions together, the cross-bolt on the tang B is pressed against the upper portion of the gravity-latch

just to the rear of the backward limit of the projection a' on the bracket. Now, by pressing the bolt down the gravity-latch will turn around until the bolt gets into the bottom of the slot into the bracket, when it (the gravity-latch) will then drop into position shown in Fig. 1 as soon as the bolt is down to a sufficient distance to clear the rear portion of the gravity-latch, as is above explained.

10 Having fully described the objects, uses, advantages, and construction of my device, what I desire to secure by Letters Patent, and what I therefore claim, is—

15 1. In a thill coupling, the combination, with a bracket having an angular slot vertical at its lower end and diagonal at its upper or open end, of a gravity-latch pivoted to the bracket directly above the bottom of the slot, over-reaching the slot, and provided with a shoulder 20 at or approximately at right angles to the slot

in the bracket, the said shoulder adapted to rest above the cross-bolt of the tang when the parts are in their normal positions, as set forth.

2. In a coupling of the character described, the bracket having an angular slot vertical at the lower and diagonal at its upper or open end, in combination with a gravity-latch properly curved, and which is adapted to be lifted up and turned round to clear the cross-bolt and tang independent of the movement 25 of the cross-bolt, substantially as and for the purposes set forth.

In testimony that I claim the above as my invention I have hereunto set my hand in the presence of two subscribing witnesses.

ALOYSIUS McHUGH.
